UNITED STATES PATENT OFFICE.

WILLIAM JAMES LANE AND GEORGE LANE, OF POUGHKEEPSIE, NEW YORK,
ASSIGNORS TO THE LANE MOTOR VEHICLE COMPANY, A CORPORATION
OF NEW JERSEY.

MOTOR-VEHICLE.

SPECIFICATION forming part of Letters Patent No. 690,161, dated December 31, 1901.

Application filed March 6, 1901. Serial No. 50,136. (No model.)

To all whom it may concern:

Be it known that we, WILLIAM JAMES LANE and GEORGE LANE, citizens of the United States, residing at Poughkeepsie, county of 5 Dutchess, State of New York, have invented certain new and useful Improvements in Motor-Vehicles, of which the following is a specification.

Our invention relates to motor-vehicles of 10 the type designed to be operated by steam.

Our invention consists in a construction whereby the air-pressure exerted over the fuel in the fuel-supply tank may be maintained constant whether the vehicle be in motion or 15 at rest, and, further, a reserve air-supply maintained for use in the fuel-tank after the fuel-tank has been emptied and refilled.

Our invention further relates to various details of construction of the air-pump, the 20 means by which the pressure of the air-pump may be regulated, as well as various other details, which will be set forth in the specification and pointed out in the claims.

The object of our invention is to automatically maintain a constant or approximately 25 constant air-pressure over the liquid fuel in the fuel-tank of the vehicle, and thereby provide for a constant pressure of the fuel delivered to the burner.

30 In all motor-vehicles of which we are aware the air-supply is created by a hand-pump, with the result that the pressure over the fuel-supply is a constantly-decreasing quantity and the fuel is supplied to the burner at 35 a decreasing pressure, with the result that it is practically impossible to regulate the quantity of fuel supplied to the burner in accordance with the work, a result which is most perfectly accomplished by our improved construction.

40 The accompanying drawings will serve to illustrate our invention, in which—

Figure 1 is a longitudinal section of a motor-vehicle and escape-flue for the products of 45 combustion, the air, naphtha and water tank, engine, boiler, and pipe connections being shown in elevation. Fig. 2 is a plan view. Fig. 3 is a perspective view of the engine, showing the relation of the air and water 50 pumps to the engine. Fig. 4 is a detail in

section of the air-pump and the regulating-valve for the pump. Fig. 5 is a detail, partially in elevation and partially in section, of the air-tank, air-gage, and controlling-valves. Fig. 6 is a diagram intended to illustrate the 55 operation of the air-pump.

In the drawings, 10 indicates the body of a motor-vehicle. The body shown is that of an ordinary one-seated vehicle commonly known as a "runabout." We, however, may use 60 any form of vehicle-body to which our apparatus may be adapted.

Located under the seat of the vehicle is a water-tank 11, and behind the water-tank is a vertical-tube boiler 12, and under the boiler 65 a burner 13. Any type of boiler and burner may be employed. Located in front of the seat is a fuel-tank 14, and in front of the fuel-tank an air-tank 15.

Located below the vehicle-body is a steam-motor device 16. Situated at the back of the vehicle is a vertical flue 17, which communicates with the horizontal flue 18, located over the boiler. The flue 17 is open at the top and bottom and communicates at the top 70 with a transversely-disposed flue 19, which is open at its ends 20. We do not in any wise limit ourselves to the particular arrangement or disposition of the flues for the products of combustion. We prefer, however, that the 75 top of the boiler should communicate with the atmosphere by an upturned flue, and we may or may not use a downturned flue, like flue 18, through which the whole or a portion of the products of combustion may be forced 80 by the action of a steam-jet or other propelling force.

21 indicates a live-steam pipe from boiler to steam-motor device; 22, a throttle-valve in this pipe; 23, an exhaust-pipe from steam- 90 motor device to vertical flue 17.

The steam-motor device 16 may be of any suitable type; but we prefer to use a two-cylinder engine, as shown in Fig. 3. Connected to the left-hand side of this engine and within 95 the casing 24, which wholly incloses the engine, is an air-pump 25. The piston 26 of air-pump 25 is rigidly connected to the piston 27 of the left-hand engine. Consequently the pump and engine pistons have a corre- 100

sponding movement—that is to say, the pump-piston moves at the same speed as the engine-piston and has a definite stroke.

Situated outside of the engine-casing is a regulating-valve for the air-pump. This valve consists of a body 28, provided with the threaded hub 29 on its right-hand side, through which the body is connected to the pump-cylinder by means of the exteriorly-threaded tube 30. The upper end of the body is also threaded to receive the adjusting-screw 31 for the valve 32 and is also threaded at the bottom to receive the adjusting-screw 33 for the valve 34. The valves 32 and 34 are provided with winged guides. Situated opposite the guides of the valve 32 is a screw 36, adjustable in the threaded opening 37 of the body 28.

Having reference now to Fig. 6, the drawing on the right indicates the clearance-space under the pump-piston 26 when the parts are in the position shown in Fig. 4—that is to say, when the pump has the smallest clearance-space beneath it—the drawing on the left indicating the clearance-space when the screw 36 is moved outward, as indicated at the dotted lines, to increase the clearance-space. Connected also to the body 28 is a pipe 38, leading to the under side of the air-tank 15, thence to air-gage 39, and by pipe 40 to the upper part of fuel-tank 14. 41 indicates a valve between pipes 38 and 40; 42, a pipe from fuel-tank to injector at burner, (indicated in the drawings at 43;) 44, a fuel-valve in the pipe 42. 45 is an air-valve in the pipe 38, through which air may be introduced in the air-tank 15 by means of a hand-pump, if desired.

The operation of our device may be described as follows: When the burner is ignited, the products of combustion pass through the burner, thence to the horizontal flue 18, to the transverse flue 19, and out of the side openings 20 of this flue. As soon as the engine or other form of steam-motor device is started the air-pump piston is also set in motion. The upward movement of the piston causes the valve 34 to be lifted and air to enter into the clearance-space under the piston and between the valves 32 and 34. As the piston of the pump descends it compresses the air in the clearance-space and lifts the valve 32, the air passing through the pipe 38 to the air-tank 15 and resisted in its pas-

sage by the pressure of the air from within 55 the tank. As the movement of the pump-plunger continues through the action of the engine the air-pressure in the tank 15 gradually increases until the pressure over the valve 32 is equal to the pressure under the 60 valve 32. When this point is reached, the valve 34 will no longer open and the pump-piston 26 will work in dead-air. The pressure which the pump-piston will exert will depend upon the amount of clearance-space. 65 The greater the clearance-space the less the pressure. Should it be desired after the air-tank has been pumped up to open the naphtha-tank for the purpose of introducing fresh fuel or for other reason, the valve 41 between the 70 pipes 38 and 40 can be closed. By doing so the air under pressure will be confined within the air-tank and the only loss of air will be that which at the time exists over the fuel in the fuel-tank. After the fuel-tank has been 75 filled and closed the valve 41 can be opened, when air from the air-tank 15 will be conveyed through the pipes 38 and 40 to the fuel-tank, as before.

By the arrangement of parts as described 80 it will be observed that air-pressure is always available, whether the vehicle be at rest or in motion, and without the employment of any auxiliary pump.

Having thus described our invention, we 85 claim—

1. In a motor-vehicle, the combination of a steam-engine, an air-pump having a definite stroke and driven by the engine, a casing inclosing the engine and pump, and a 90 pressure-regulating valve for the pump located external to the casing.

2. In a motor-vehicle, the combination with the vehicle-body, of a motor device suspended below the vehicle-body, an air-pump carried by the motor device and independent of the body of the vehicle, an inclosing casing the casing wholly enveloping the air-pump and engine, an air-tank, a fuel-tank, and the interposed pipe connections. 95

In testimony whereof we affix our signatures in presence of two witnesses.

WILLIAM JAMES LANE.
GEORGE LANE.
